UNITED STATES PATENT OFFICE.

HENRY KAEMPF, OF GLADSTONE, MICHIGAN.

GAUGE COCK.

1,412,530.

Specification of Letters Patent. Patented Apr. 11, 1922.

Application filed January 19, 1920. Serial No. 352,813.

To all whom it may concern:

Be it known that I, HENRY KAEMPF, a citizen of the United States, and resident of Gladstone, in the county of Delta and State 5 of Michigan, have invented certain new and useful Improvements in Gauge Cocks; and I do hereby declare that the following is a full, clear, and exact description thereof.

This invention relates to gauge cocks and 10 more particularly to the specific parts constituting the valve and valve seat.

The primary object of my invention consists in providing a gauge cock of this character, with a valve member so constructed 15 and associated with the various parts of the gauge cock as to eliminate wear upon the valve and valve seat.

A more specific object resides in the provision of a valve member so constructed that 20 proper alinement and seating of the same is assured.

A further object of my invention is to provide a separable valve unit or member associated with a one-piece valve housing where- 25 in provision is made to assemble or renew the valve unit by passing the same through the valve stem opening, which opening is of greater diameter than the head of the removable valve member. By making a pro- 30 vision of this character I have been able to produce a valve of minimum cost with provision for removing the valve unit in a sim- ple manner.

With these objects in view the invention 35 comprehends certain details of construction and peculiar arrangement of parts such as will be described and specifically pointed out in the appended claim.

In the accompanying drawing:

40 Figure 1 represents a gauge cock embodying the features of my invention the same being broken away and in section to more clearly illustrate the points of the invention.

45 Figure 2 is a detail sectional view taken upon the line 2—2 of Figure 1.

Figure 3 is a detail view of the valve member.

At the present time it is common custom 50 in the construction of gauge cocks and similar types of valves to construct the valve member integral with or rigidly secure the same to the actuating handle. From this construction it will be seen that rotary move- 55 ment of the actuating handle will cause the valve member to be revolved upon its seat,

and inasmuch as cocks of this nature are used where a high pressure is employed, it becomes necessary to obtain a very tight closure of the valve, which causes a great friction between the valve and valve seat, and due to the rotary movement of the valve portion upon the seat, undesired wear between these members results. Furthermore where the valve is rigidly secured to the actuating handle or formed integral therewith it is somewhat difficult and expensive to obtain a proper and exact alinement between the valve and valve seat whereby a perfect closure is assured. 70

These objectionable features have been overcome in the construction of my invention as shown in the drawing, in which a one-piece valve housing, designated by the numeral 1, is provided with an extension 2, 75 having a valve stem opening which is threaded interiorly to receive a valve actuating stem 3, and provided exteriorly with a customary packing gland 4. The opposite side of the housing 1 is provided with an inlet port 5, 80 in alinement with the valve actuating handle and adapted to receive the grooved shank 6, of a valve member 7, the same being provided with a head portion 8 adapted to form a closure for the valve seat 9 at the interior 85 end of the inlet port 5.

The interior portion 10 of the actuating stem 3 is adapted to abut the valve head 8 and is rounded at its end, in order to eliminate friction between the same and the valve. 90 By referring to Figure 1 of the drawings it will be seen that the threaded valve stem opening of the one piece housing is of greater diameter than the diameter of the circular head 8 of the valve member and hence it will 95 be readily seen that in assembling the structure this valve unit 8 can be dropped through the valve stem opening to its seat. It also shows that should the valve member wear and require repairs, the simple valve unit 100 which is worn can readily be renewed and a new one substituted by unscrewing the cap 4 and valve stem, whereby access may be had to withdraw the valve member from the housing without dismantling any of the 105 parts or without depending upon a skilled mechanic for repairs.

From this construction it will be readily seen that as the actuating handle 3 is revolved in one direction, it will permit the 110 valve 7 to be opened, due to the fluid pressure exerted upon the same, while manipu-

lation of the actuating handle in the opposite direction will cause the end portion 10 to abut the valve and force the same upon its seat, and because of the abutting engagement between the end portion 10 and the valve 8, rotary movement of the actuating handle will not be transmitted to the valve, thereby eliminating any grinding wear between the valve and its seat. As the actuating handle is released or run out and the valve permitted to raise from its seat, fluid will pass through the inlet port around the grooved shank of the valve, while at the same time, the shank having a bearing in the inlet port, holds the valve in proper alignment with its seat.

What is claimed is:

In a gauge cock embodying a one piece housing having an alined valve seating inlet port and a threaded valve stem opening, the latter being of greater diameter than the inlet port, the wall surrounding the inlet port having an annular upwardly extending rib forming the valve seat; the combination of 25 a removable valve member comprising a flat

head adapted to engage the inlet port seat, and a grooved shank portion having a bearing in said outlet port to hold the valve head in alinement with said seat, said shank portion being considerably longer than the diameter of said inlet port, the head being of less diameter than the valve stem opening, whereby said valve member may be passed through the opening for assemblage or renewal, and a valve stem in threaded engagement with the valve stem opening, the stem terminating with an integral finger portion provided with a rounded end, which is adapted to have a single point engagement with the flat head of the valve to hold it upon its seat, whereby frictional engagement of the finger and head is reduced to a minimum, the valve stem element being entirely separate from the removable valve member.

In testimony that I claim the foregoing I have hereunto set my hand at Gladstone, in the county of Delta and State of Michigan.

HENRY KAEMPF.
